UNITED STATES PATENT OFFICE.

WILLIAM R. KNIGHT, OF BELLEVILLE, NEW JERSEY, ASSIGNOR TO ST. MUNGO MANUFACTURING COMPANY OF AMERICA, OF NEWARK, NEW JERSEY, A CORPORATION OF NEW JERSEY.

PLAYING-BALL.

1,192,831.

Specification of Letters Patent. Patented July 25, 1916.

Application filed September 18, 1915. Serial No. 51,339.

To all whom it may concern:

Be it known that I, WILLIAM R. KNIGHT, a subject of the King of Great Britain, and a resident of Belleville, county of Essex, 5 and State of New Jersey, have invented new and useful Improvements in Playing-Balls, of which the following is a specification.

The object of the invention is to construct a playing-ball with means which will aid its 10 flight and which will place the ball under control in all departments of the game in which it is employed.

The invention preferably relates to that class of playing-balls which are especially 15 adapted for the purpose of golf and which have a liquid center.

In performing my invention a playing-ball having such a center is provided with one or more balls which are free to move 20 about in the liquid contained in the playing-ball and which balls have a specific gravity greater than said liquid.

As showing a specific embodiment of the invention reference is made to the drawing 25 forming a part of this specification and in which drawing—

Figure 1 discloses a playing-ball partially broken away so as to show its construction. Figs. 2, 3 and 4 show cores of different construction which may be used in the manufacture of playing-balls that embody my invention.

The playing-ball comprises a bag, container or receptacle A that is filled with a liquid B. Around this bag or container A there is preferably wound, under a high degree of tension, a rubber tape that may be for example approximately one inch in width. This rubber tape is comparatively 30 thin but when wound under a high degree of tension imparts great pressure upon the liquid in the bag or container A. The windings of tape are indicated by the reference character C and around them there is wound under a high degree of tension what may be considered a thread of rubber, which thread before winding may be approximately $\frac{1}{2}$ of an inch in width, these windings of rubber thread being indicated by the reference 40 character D. Finally there is placed upon and around these windings any suitable wear-resisting casing E, for example of gutta percha. The bag or container A that is shown in Fig. 1 is of the same construction as that shown in Fig. 3 in that the bag

or container comprises a fabric portion a surrounded by a rubber portion b. This fabric is provided in order to protect the rubber portion from the blows that are imparted to the bag by the ball F. This ball 60 has a specific gravity heavier than the liquid and may be made for example of weighted rubber or metal or composition.

The parts which are shown in Figs. 2, 3 and 4 may be considered the cores of the 65 playing-balls of which they substantially constitute a part and from an inspection of the drawing it will be seen that they are made by placing in the bag or container the ball F and liquid B and then tying the 70 throat or neck of the bag by a rubber thread c.

In the form of core shown in Fig. 2 there is not provided any fabric a in combination with the rubber portion b and while 75 such a bag or container will serve a limited period of time still it will not be as successful as a bag which is reinforced or protected by a layer of fabric or the equivalent thereof.

The bag which is used in the core shown 80 in Fig. 4 comprises the fabric a that is covered on the exterior and interior by layers of rubber b and b'. The inner layer b' of rubber of course serves to protect the fabric a and the fabric a—which serves as a reinforcing material—in turn serves to protect the outer layer of rubber b, thus making a 85 bag having certain advantageous features.

A considerable advantage is derived from placing the ball F that is heavier than the 90 liquid in the liquid that is contained within the core. In the first place the flight of the playing-ball is increased; moreover, when the playing-ball is given what is known by players as a back-spin it will fall dead; this 95 evidently resulting from the ball F having a certain inertia and tending to remain still while the remainder of the playing-ball including the liquid tends to rotate and thus the ball F acts as a damper upon the liquid 100 to brake or retard the movement of the liquid and, consequently that of the rest of the playing-ball structure.

As previously stated the ball F is of a material that is of a specific gravity greater 105 than the liquid B and the ball F if made of a hard composition or a metal such as hardened steel should be given a smooth surface in order that the ball may not puncture the bag or container A. While there is shown 110

only one ball within the liquid still a plurality of balls may be employed if desired.

The improvements herein set forth are not limited to the precise construction and arrangement shown and described, as they may be embodied in various forms and modifications without departing from the spirit and scope of the invention.

What I claim is:

- 10 1. A playing-ball comprising in combination a rubber bag or container filled with liquid and containing therein a metal ball, windings in the form of a rubber tape surrounding said bag, windings in the form of a rubber thread surrounding the windings of tape, and a wear-resisting casing on the exterior of said windings.
- 15 2. A playing-ball comprising in combination a container having therein a liquid and a ball free to move in said liquid, windings of rubber surrounding said container, and a wear-resisting casing surrounding said windings.
- 20 3. A playing-ball comprising in combination a container having therein liquid and a ball having a specific gravity which is greater than that of the liquid, windings surrounding said container, and a wear-resisting casing surrounding said windings.
- 25 4. A playing-ball comprising in combination a container of rubber having a layer of fabric for protecting the rubber and having in the container a liquid and a ball of specific gravity greater than the liquid, which ball is free to move in said liquid; windings of rubber surrounding said container, and a wear-resisting casing surrounding said windings.
- 30 5. A playing-ball having in combination a bag comprising a layer of rubber and a layer of fabric, liquid filling said bag, a member or members in said liquid which member or members have a specific gravity greater than the liquid, rubber windings about said bag, and a wear-resisting casing constituting the outer portion of the playing-ball.

6. A playing-ball having a core which comprises a bag having a layer of fabric or other reinforcing material and a layer of rubber, an incompressible liquid in said bag, and a smooth hard ball in said bag, windings about said bag, and a wear-resisting casing constituting the outer portion of the playing-ball.

7. A core for playing-balls comprising in combination a casing having a layer of fabric or other reinforcing material, liquid filling said casing, and a ball free to move in said liquid.

8. A playing-ball comprising in combination a liquid-tight bag having a layer of fabric or other reinforcing material, liquid filling said bag, and a ball free to move in said liquid, the fabric or other reinforcing material being provided to protect the bag from injury by said ball; windings of rubber surrounding said ball, and a wear-resisting casing surrounding said rubber windings.

9. A playing-ball comprising in combination a receptacle containing liquid, a ball free to move in said liquid, rubber windings surrounding said receptacle, and a wear-resisting casing upon and surrounding said rubber windings, said ball being of a higher specific gravity than the liquid in which it is contained.

10. A playing-ball comprising in combination a receptacle, a liquid contained therein, a ball free to move in said liquid, windings of rubber mounted upon and surrounding said receptacle, and a wear-resisting casing upon and surrounding said rubber windings, the casing containing the liquid comprising as a part thereof a layer of fabric or other reinforcing material.

This specification signed and witnessed this 17th day of September, A. D. 1915.

WILLIAM R. KNIGHT.
